UNITED STATES PATENT OFFICE.

HECTOR V. LOUGH, OF NORTH PLAINFIELD, NEW JERSEY.

TABLET.

SPECIFICATION forming part of Letters Patent No. 778,254, dated December 27, 1904.

Application filed March 15, 1904. Serial No. 198,199.

To all whom it may concern:

Be it known that I, HECTOR V. LOUGH, a subject of the King of Great Britain, and a resident of North Plainfield, in the county of Union and State of New Jersey, have invented 5 a new and useful Improvement in Tablets, of which the following is a specification.

My invention relates to an improvement in tablets, and is directed more particularly to 10 certain improvements in that class of tablets in which one or more cards may be swung in either direction from one position in the tablet to the front or back thereof for the purpose of quickly exposing the face of a desired 15 card irrespective of its position in the tablet.

A further object is to provide certain improvements in the several parts of the tablet which forms the subject-matter of United States Letters Patent No. 744,578, granted to 20 me the 17th day of November, 1903.

A practical embodiment of my invention is represented in the accompanying drawings, in which—

Figure 1 represents my improved tablet in 25 front elevation. Fig. 2 is a back view of the same. Fig. 3 is a view showing one of the cards in an intermediate point which it would occupy when being swung from one position in the tablet to the front or back thereof. 30 Fig. 4 is an enlarged view of the top of the tablet. Fig. 5 is a view of the blank from which the hollow pivot is formed. Fig. 6 is an end view of the hollow pivot when completed to form the eye for the attachment of 35 the springs. Fig. 7 is a top view of the same. Fig. 8 is an enlarged plan view of one of the springs; and Fig. 9 is a detail view, on a much larger scale, showing the free end of the spring bent at an angle to the balance of the 40 spring.

The tablet is herein shown as comprising a plurality of cards 1, which cards may be made of celluloid or other suitable material presenting writing-surfaces thereon, if so desired. 45 This tablet is provided with a slot 2 extending from the top of the tablet inwardly to a circular hole 3 a short distance from the top of the tablet. These cards are pivoted together by a hollow pivot 4, which fits the walls 50 of the circular hole 3 through the tablet. An

eye 5 extends through the hollow pivot 4 eccentrically. This pivot 4 is preferably made from a blank 6, having cut-away portions 7 and 8, which cut-away portions form the walls of the eye 5 when the pivot 4 is completed by 55 bending the blank 6 into position.

The front and back of the tablet are engaged by two springs 9 and 10. A pin or rivet 11 passes through the eye 5 in the hollow pivot 4 and serves to secure one end of each 60 of the springs to the pivot. These springs grip the cards of the tablet between them and they are bent inwardly, thus offsetting the cards upon the opposite sides of the slot 2 in the tablet. The free end of the spring 9 is 65 bent obliquely outward away from the front of the tablet, as shown at 12, and the free end of the spring 10 is bent obliquely outward away from the back of the tablet, as shown at 13. These portions 12 and 13 of the two 70 springs serve to guide any one or more of the cards which it may be desired to swing in either direction from one position in the tablet to the front or back thereof, as the case may be. 75

The device as herein shown and described absolutely prevents any liability of a card catching when being swung in either direction. The oblique branches 12 and 13 at the free ends of the springs also tend to retain 80 the cards in their normal position.

It is evident that slight changes might be resorted to in the form, construction, and arrangement of the several parts without departing from the spirit and scope of my invention. Hence I do not wish to limit myself strictly to the structure herein set forth; but 85

What I claim is—

1. A tablet comprising a plurality of slotted cards pivoted together and oppositely arranged springs offsetting the cards on the opposite sides of the slot to permit a card to be swung in either direction from one position in the tablet to the front or back thereof. 90

2. A tablet comprising a plurality of slotted cards pivoted together and oppositely arranged springs offsetting the cards on the opposite sides of the slot to permit a card to be swung from one position in the tablet to the front or back thereof, the said springs having 95 100

branches at their free ends extended obliquely away from the tablet.

3. A tablet comprising a plurality of slotted cards, a pivot connecting them and oppositely-arranged springs carried by the pivot offsetting the cards on the opposite sides of the slot to permit a card to be swung in either direction from one position in the tablet to the front or back thereof.

10 4. A tablet comprising a plurality of slotted cards, a pivot connecting them and oppositely-arranged springs connected eccentrically to the pivot, and offsetting the cards on the opposite sides of the slot to permit a card to be 15 swung in either direction from one position in the tablet to the front or back thereof.

15 5. A tablet comprising a plurality of slotted

cards, a hollow pivot connecting them, an eye formed eccentrically in the pivot, oppositely-arranged springs, a pin passing through said eye and securing one end of the springs to the pivot, the said springs offsetting the cards on the opposite sides of the slot to permit a card to be swung in either direction from one position in the tablet to the front or back thereof.

In testimony that I claim the foregoing as my invention I have signed my name, in presence of two witnesses, this 14th day of March, 1904.

HECTOR V. LOUGH.
